GEORGE DAVIDSON AND HENRY C. DOCTOR, OF FORT WAYNE, INDIANA.

KNITTED FABRIC BODY.

1,305,446.

Specification of Letters Patent. Patented June 3, 1919.

Application filed March 6, 1918. Serial No. 220,624.

To all whom it may concern:

Be it known that we, GEORGE DAVIDSON and HENRY C. DOCTOR, citizens of the United States of America, and residents of Fort Wayne, in the county of Allen and State of Indiana, have invented certain new and useful Improvements in Knitted Fabric Bodies, of which the following is a specification.

This invention relates to improvements in knitted fabric bodies intended for making garments, and the object thereof is to form the body of several sections composed of differently formed stitches in such manner that transferring of the work from one knitting machine to another will be obviated, and also to complete the body in such manner that unraveling at the finished end, as well as at the junctures of the different sections, will be obviated.

10 The objects of the invention are accomplished by the construction illustrated in the accompanying drawings in which:—

Figure 1 is a front view of a knitted body showing the invention; and

25 Fig. 2 is a longitudinal section of Fig. 1, and similar characters of reference indicate corresponding parts in both views.

The body may be either tubular or flat in form according to the use for which it is intended. In either event, however, the body is formed in substantially the same manner and consists of a series of sections, A, B and C arranged in successive order and united with each other at their respective adjacent 35 ends, and at each end of the body is formed a corresponding welt D and E.

In making the body the welt D is first knitted and is formed in the customary manner, and likewise the section A is knitted 40 and fashioned with double stitches so that ribs are formed in the manner well known in the art. The section A may be of any suitable length or breadth or diameter. When the section A has been completed and

45 the section B, which is made with single stitches, is formed, the stitches on one side of the body are continued for one or several courses, and in making the same a fulling, felting or fleecing yarn is employed, and

50 the stitches upon the opposite side of the body are temporarily discontinued until the said one or several courses are completed.

Then the section B is formed by making stitches upon the opposite side of the body 55 and continuing the same until the desired length of the section is made. The other

stitches are "dropped off" and the lap F formed by the one or several courses of stitches is subsequently treated by any of the well known methods which are used to prevent unraveling of the yarn.

When the section B of single stitched, flat or plain knit fabric has been completed one or several courses of tuck stitches G are formed in the manner in which tuck stitches are ordinarily made and at this juncture 60 double stitching is resumed so that the section C is formed with ribs in the manner in which the section A is made. The welt E at the upper end of the section C is formed by discontinuing, momentarily, the stitches on one side of the fabric while continuing for numerous courses the stitches upon the opposite side thereof, and then uniting the stitches of both sides together, and in this 65 operation fulling, felting or fleecing yarn is again introduced and one or several courses of stitches are made so that an extended bead H is formed thereby. The bead is subsequently treated by fleecing or some such 70 similar methods ordinarily applied to prevent unraveling of the yarn.

The body thus formed and completed will retain its fabricated condition, except, of course, when impaired by wear and natural 75 deterioration, and a further advantage in thus forming the body is that the lap F formed at the juncture of the sections A and B, and the introduction of the tuck stitches G at the juncture of the sections B and C so effectively close the openings that occur 80 ordinarily when changing from double stitching to the single style and from the single style of stitching to the double or rib knit fashion. This is accomplished by making the tuck stitches upon the opposite set 85 of needles from that upon which the plain fabric is being knit.

What we claim is:—

1. A knitted fabric body formed with a 100 welt succeeded by a rib-knit section, a plain-knit section and a second rib-knit section arranged in successive order, each section being of single thickness, the latter section having formed at its outer end a welt which 105 has been completed with an extended bead made of fulling yarn.

2. A knitted fabric body formed of a series of sections of single thickness, the first section of which is formed with rib-knit 110 stitches and the second section being formed with plain-knit stitches, there being made at

the juncture of the two sections a lap adapted to close the eyelet holes in the fabric at the juncture and being formed of fulling yarn, and the third section of which is formed with rib-knit stitches, there being introduced at the juncture of the plain-knit section and the latter rib-knit section several courses of tuck-stitches adapted to close the eyelet holes in the fabric at the latter juncture.

3. A knitted fabric body formed of a series of sections of single thickness, the first section of which is formed with rib-knit stitches, the second section with plain-knit 15 stitches and the third section with rib-knit stitches and ending with a welt concluded

with several courses of stitches made of fulling yarn, there being a lap formed of fulling yarn at the juncture of the first two sections adapted to close the eyelet holes in the fabric 20 at the juncture, and there being also introduced at the juncture between the last two sections several courses of tuck-stitches adapted to close the eyelet holes in the fabric at the latter juncture.

In testimony whereof we affix our signatures, in presence of two witnesses:

GEORGE DAVIDSON.
HENRY C. DOCTOR.

Witnesses:

SOPHIA HEINE,
MATILDA METTLER.
